UNITED STATES PATENT OFFICE.

JOHN M. PEAY, OF PEMBROKE, KENTUCKY, WILLIAM A. PEAY, OF MILTON, TENNESSEE, AND J. HAM HELSLEY, OF PARADISE, KENTUCKY.

AUTOMATIC FAN.

SPECIFICATION forming part of Letters Patent No. 339,011, dated March 30, 1886.

Application filed December 24, 1885. Serial No. 186,587. (No model.)

To all whom it may concern:

Be it known that we, JOHN M. PEAY, WILLIAM A. PEAY, and J. HAM HELSLEY, citizens of the United States, residing at Pembroke, in the county of Christian and State of Kentucky, and Milton, in the county of Rutherford and State of Tennessee, and Paradise, in the county of Muhlenburg and State of Kentucky, respectively, have invented a new and useful improvement in Automatic Fly-Brush and Caster, combined, of which the following is a specification, reference being had to the accompanying drawings.

Our invention relates to improvements in combined automatic fly-brushes and table-casters; and the novelty consists of the peculiar construction, combination, and adaptation of parts, substantially as hereinafter fully set forth, and specifically pointed out in the claims.

In the accompanying drawings, Figure 1 is an elevation, and Fig. 2 is a vertical sectional view, of our improvements. Fig. 3 is an enlarged detail view of parts of our improvements; and Fig. 4 is a plan view of the parts shown in Fig. 2, looking on the driving mechanism.

Referring to the drawings, in which like letters of reference denote corresponding parts in all the figures, A designates the base of our improved combined automatic fly-brush and caster, which is provided with projecting feet or an annular depending flange, a, to elevate the bottom thereof out of contact with the table or other place on which the device is placed. This base is made hollow to provide an inclosing casing for the driving clock-work mechanism B, and the upper wall of said case or base is made curved and pointed, as at a', to provide a bearing for the horizontally-rotating supporting-ring C, that carries the bottles e of the caster. This base and the ring C may be finished to any desired fanciful degree, and the upper wall of the case is made detachable, for the purpose of permitting easy access to the driving mechanism.

We prefer to employ the following described driving mechanism for rotating the vertical shaft D, to-wit: A closed driving-spring, f, that is mounted on a winding-shaft, f', which

projects at one end through the bottom of the base or case A, to adapt the spring to be conveniently wound by a key or other suitable device, a gear-wheel, f², rigidly secured on the winding-shaft above the spring, and meshes with a pinion, f⁴, which pinion is secured on a shaft, f⁵, that also carries a gear-wheel, f⁶. This latter-named gear-wheel meshes with and actuates a pinion, f⁷, the shaft of which carries a pinion, f⁸, which drives a gear-wheel, f⁹. The shaft of the gear-wheel f⁹ is provided with a horizontally-rotating balance-wheel, f¹⁰, and the lower end of the vertical shaft D is secured or stepped in and rotated by the shaft of the balance and gear-wheels, f¹⁰ f⁹. Near its lower end the vertical tubular upright E has a base, d, that bears on and is secured to a bracket, d', and this shaft D is arranged within said upright and concealed and protected thereby. To the upper end of the tubular upright is rigidly secured a collar, g, of a supporting-frame, G, which comprises two vertical arms, g', and a horizontal arm, g², an opening being provided through the collar and the horizontal arm for the passage of the upper end of the rotating shaft D. To the upper end of the shaft D is rigidly keyed or otherwise suitably secured a crank-wheel, H, which has an opening near its outer periphery, and through this opening passes the lower end of a crank pin or rod, h. The upper end of this crank pin or rod h is bifurcated, and the diverging arms provided thereby are pivotally connected to studs or trunnions of a horizontally-disposed shaft, I. The ends of the shaft I are hollowed or recessed out to provide conical bearings that receive the pointed ends of journal pins or studs I', said studs being rigidly and removably secured in the upper ends of the vertical arms g' of the frame G.

J J designate the fan or brush carrying shafts or arms that are disposed in parallel horizontal planes on opposite sides of the vertical frame G, the inner ends of each of the shafts or arms J having an upwardly-curved or bow-shaped arm, j, that extends over the upper end of the vertical arms g' of the vertical frame G and is secured to the end of the shaft I. If desired the shafts or arms J, the arms j, and the shaft I may constitute a single cast-

ing or be made separate, and the brush-carrying arms J may be made in foldable telescopic sections.

The extremities of the arms or shafts J are provided with depending rods or shafts K, which carry cross-bars k at their lower ends, to which cross-bars are secured a series of depending beater-fingers, k'. The cross-bars k may have suitable braces between them and the vertical arm K, and the beater-fingers provided with strips of paper, fabric, &c.

L designates a similar brush or fan secured directly to each of the shafts or arms J between its bearing and the depending arm K. This brush consists of two bars, l, suitably secured to and parallel with the shaft J, and having the radial fingers l', that are provided with the strips of paper, &c.

M designates two upwardly-extending arms or rods, that are rigidly secured on the shaft I and connected at their upper end by a transverse bar, m. This bar m has a threaded opening or socket therein, which is located immediately over the vertical shaft D and the point of pivot-connection between the shaft I and the crank pin or arm h.

N designates a threaded shaft, which is mounted in the threaded socket of the bar m, and is vertically adjustable therein, and at its upper end is provided with the horizontally-disposed threaded arm n, on which is adjustably mounted a balance-weight, N'. The arm n is connected to the shaft N by the intermediate arms, n' n'', and the balance-weight is provided with a threaded socket or opening, and a serrated projecting rim, for its convenient manipulation by hand.

The operation of our invention is as follows: When the drive-spring f is set in motion it will rotate the train of gearing and the vertical shaft D continuously. The eccentric or crank wheel or disk is thus continuously rotated by the shaft D; but the crank arm or pin h converts the rotary motion of the continuously-rotating disk into an oscillating movement, and imparts such oscillating motion to the shaft I and the brush-carrying arm or arms J. These arms or shafts are thus caused to rock or swing back and forth in vertical planes, and to swing the brushes thereof to and fro, to keep the table clear of flies and other obnoxious insects. The balance-weight N' can be adjusted laterally on its arm, and the shaft N can be adjusted vertically to regulate the stroke or swing of the horizontal brush-carrying arms. The brush-carrying arms or shafts J are made of very light material, and as they are located on opposite sides of the vertical shaft D and frame G they counterbalance each other and run or oscillate very smoothly, uniformly, and steadily.

The operation of the device is very similar to clock-work, the brush-carrying arms serving as the pendulum to impart the necessary momentum and force after the operation has been once started. The driving mechanism

B furnishes the requisite power to oscillate the pendulum-like rock-arms that carry the brushes, and the vertical shaft D transmits the motion of the driving mechanism to the rock or oscillating brush-arms.

The various shafts of the clock-work-driving mechanism are provided with suitable bearings, and the several connections between the various parts may be changed without departing from the principle or sacrificing the advantages of our invention.

Having thus described our invention, what we claim as new, and desire to secure by Letters Patent, is—

1. The combination of a tubular standard having a base at its lower end and a frame at or near its upper end, a driving mechanism inclosed within the base, horizontal brush-carrying arms journaled on the frame, a driving-shaft arranged within the tubular standard and rotated by the driving mechanism, and a device for transmitting and converting the motion of the driving-shaft to the brush-carrying arms, substantially as described. 85

2. The combination of a tubular standard having a base, driving mechanism inclosed within the same, a driving-shaft rotated by said mechanism, horizontal brush-carrying arms journaled on the standard, a crank-wheel supported on the driving-shaft, and a rod connecting the crank-wheel and brush-arms, substantially as described. 95

3. The combination of a standard having a base, the driving mechanism inclosed within the base, a shaft, the horizontal brush-arms journaled on the standard and oscillated by mechanism intermediate of the arms and shaft, a bracket mounted on the arms, and a weighted vertically-adjustable standard supported in the bracket, substantially as described. 100

4. The combination of a standard, brush-carrying arms journaled thereon, mechanism for oscillating the arms, a bracket, M, supported on the arms, and a vertically-adjustable standard mounted in the bracket and carrying a laterally-movable balance-weight, substantially as described. 110

5. The combination of a tubular standard having a base, a driving mechanism inclosed within the base, a driving-shaft carrying a crank-wheel, a frame, G, secured on the standard, the bearings I, supported in the frame, the horizontal brush-carrying arms journaled on the said bearings, and a rod, h, connected to the crank-wheel and brush-arms, substantially as described. 115

6. The combination of the driving-shaft, the oscillating brush-supporting arms connected to the shaft and driven thereby, and a horizontally-adjustable weight over the driving-shaft, substantially as described. 125

7. The combination of a supporting-stand, a frame mounted thereon, a driving-shaft carrying a crank, the oscillating brush-supporting arms, a crank pin or rod, a vertically-adjustable shaft on the oscillating arms, and a laterally-movable balance-weight on an arm 130

of said adjustable shaft, substantially as described.

8. The combination of a base, a tubular standard, a horizontally-rotating easter-ring 5 mounted on the base, a driving mechanism located in the base, a rotating shaft operated by said mechanism and carrying a crank-wheel, a frame, G, having the journals, the oscillating shafts mounted on the journals and provided with the brushes K L, and a crank-pin 10 connected with the crank-wheel and having bifurcated arms pivoted on the oscillating brush-arms, substantially as described.

In testimony that we claim the foregoing as

our own we have hereto affixed our signatures 15 in presence of two witnesses.
